Attorney

UNITED STATES PATENT OFFICE.

RAYMOND D. VINER, OF OGDEN, UTAH.

COLLAPSIBLE BUCKET.

1,385,934.

Specification of Letters Patent. Patented July 26, 1921.

Application filed December 30, 1919. Serial No. 348,259.

To all whom it may concern:

Be it known that I, RAYMOND D. VINER, a citizen of the United States, residing at Ogden, in the county of Weber and State of Utah, have invented certain new and useful Improvements in Collapsible Buckets; and I do hereby declare the following to be a full, clear, and exact description of the invention, such as will enable others skilled in the art to which it appertains to make and use the same.

My invention relates to collapsible or telescopic buckets, its principal object being to provide a bucket which may be collapsed when not in use and which will be positively held in extended position when in use.

A further object of the invention is to provide a collapsible bucket which may be quickly arranged in extended position and may be readily folded in compact form when not in use.

Another general object of the invention is to provide a bucket or pail which is simple in construction, consists of few parts, and may be manufactured at a minimum cost.

With the above and other objects and advantages in mind, the invention consists in the novel combination of elements, construction and arrangement, operation and specific features all of which are to be hereinafter fully enlarged upon and specifically defined in the subjoined claim, the invention being illustrated in the attached drawings wherein:

Figure 1 is an elevation of the bucket in extended position;

Fig. 2 is a like view of the bucket in collapsed position;

Fig. 3 is a fragmentary detail view illustrating one of the hinged bars for retaining the bucket in extended position and the latch associated therewith.

My improved bucket consists of a plurality of telescopic sections 5 fitted within each other with sufficient tightness to afford watertight joints. The lowermost section is provided with a bottom wall 6 and an outwardly circumferential horizontally disposed annular flange 7 while the uppermost section is provided with a circumferential horizontally disposed flange 8.

In order to retain the bucket against collapsing when in use there is provided a pair of bars 9 which are disposed at diametrically opposite points on the bucket and have their

upper ends hinged to the circumferential flange 8 through the medium of hinges 10. These bars are so arranged as to lie against the sections and have their ends abutting the flanges 7 and 8 respectively when the sections are in extended position. When the bucket is collapsed the bars 9 are folded inwardly upon the outer section 5 as illustrated in Fig. 2. The lower ends of each of the bars is slotted as at 11 and movable therein is the pivoted latch 12 adapted to engage the openings 13 in the flange 7 to retain the bars against accidental displacement. A finger engaging member 13' is pivotally mounted adjacent each of the latches 12 and is pivotally connected with its respective latch as at 14. Coil springs 15 are provided which are accommodated in the slotted ends of the bars and bear against the inner end of the finger engaging members 13' and project 75 these latches into engagement with the openings in the flange 7 in the lower section 5. It will be seen that pressing the finger engaging members downwardly the latches will be retracted from the flange 7 to permit 80 the bars to be swung upwardly upon the ends and disposed across the uppermost section.

The construction shown and described in the practical embodiment of the invention 85 but it will be understood that the same may be modified in many respects, and that my limits of such modification are only governed by the subjoined claim.

What is claimed is:

A bucket comprising a plurality of telescopic sections, the top and bottom sections having outwardly extending projections, bars having their extremities engaging the inner faces of said projections to hold the bucket extended, means hingedly connecting the upper ends of the bars to the upper section to admit of the bars folding over the bucket, latches carried by the lower ends of the bars to positively and detachably engage 100 the lower projection, and spring controlled finger engaging members mounted upon the bars for operating the said latches.

In testimony whereof I affix my signature in presence of two witnesses.

RAYMOND D. VINER.

Witnesses:

E. W. CANNADY,
REBECCA CANNADY.
